UNITED STATES PATENT OFFICE.

PAUL WAGNER, OF SACO, MONTANA.

JACK.

1,229,833.

Specification of Letters Patent. Patented June 12, 1917.

Application filed June 6, 1916. Serial No. 101,973.

To all whom it may concern:

Be it known that I, PAUL WAGNER, a citizen of the United States, residing at Saco, in the county of Phillips and State 5 of Montana, have invented new and useful Improvements in Jacks, of which the following is a specification.

This invention relates to a lifting jack and more particularly to that type of jack 10 which is provided with mechanism for raising the load carrying bar step by step.

The primary object of the invention is to provide a lifting jack of this character which is constructed in such a manner as 15 to render the same capable of withstanding considerable strain when in use.

Another object of the invention is to provide a jack in which the load carrying bar is received in a collar pivotally connected 20 with a link having a cam-face and connected with the load carrying bar raising mechanism in such a manner that when said mechanism is operated the cam-face on the link will be brought into engagement 25 with the load carrying bar and co-act with the collar in forming a clutch by means of which the load carrying bar may be raised step by step.

With these and other objects in view, the 30 invention resides in the novel combination and arrangement of parts, which will be hereinafter described and particularly pointed out in the claim.

The preferred embodiment of the invention has been illustrated in the accompanying drawing, although no restriction is necessarily made to the precise details of construction therein shown, as changes, alterations, and modifications within the 40 scope of the claim may be resorted to when desired.

Like characters of reference denote corresponding parts throughout the several views in the drawing, in which:

45 Figure 1 is a side elevation partly in section of a jack constructed in accordance with the invention and showing the load carrying bar raised one step.

Fig. 2 is a vertical longitudinal sectional view through the jack showing the lever included in the load carrying bar raising mechanism in a position in which the clutch associated with said mechanism is released from engagement with the load 50 carrying bar.

Fig. 3 is a transverse sectional view on the line 3—3 of Fig. 1.

Fig. 4 is a detail view of the clutch associated with the load carrying bar raising mechanism disconnected from the jack. 60

Referring now to the drawing in detail, the numeral 1 designates an elongated and rectangular shape base which may be formed from any suitable material, said base having connected therewith between its ends a support 2, forked as at 3, to provide spaced parallel arms 4.

The base is provided adjacent the support 2 with a transversely extending opening 5, while each arm 4 has formed therein a row of spaced and transversely extending openings 6.

Secured to the base 1 and support 2 is an L-shaped bracket 7 which assists in connecting the support 2 with the base 1 and serves as a brace therefor.

A plate 8 extends longitudinally of the support 2 for a portion of its length and is provided with an arm 9 arranged at right-angles to the plate and connected with the base 1 to enable the plate to assist in connecting the support to the base and serving as a brace for the support, said arm having formed therein an opening 10 registering with the opening 5 in the base. 85

The other end of the plate 8 has formed thereon a short arm 11 arranged at right-angles to the plate and in spaced relation with the arm 9, said arm being provided with an opening 12 alining with the opening 10 in the arm 9 and enabling the arm to serve as a guide for a load carrying bar hereinafter described. 90

A bracket 13 extends at right-angles to the arms 4 and has formed thereon at one end a head 14 alining with the arm 11 and provided with an opening 15 registering with the opening 12 in said arm. 95

The other end of the bracket 13 is forked to provide arms 16 each of which is bent to provide a portion lying at a right-angle to the head 14, said arms being connected with the arms 4 by bolts 17 to enable the bracket 13 to serve as a brace for the free ends of said arms. 100

A load carrying bar 18 passes through the openings in the head 14 and arm 11 and has one end thereof received in the opening 5 in the base, the other end of the load carrying bar which extends above the opening 15 is forked to form a head 19. 110

A collar 20 loosely encircles the load carrying bar above the head 14 on the bracket 13, said collar being provided with a

laterally extending arm 21 terminating at its free end in a tapered gripping finger 22 adapted for contact with the upper face of the bracket 13, so that the collar 20 and arm 5 21 are normally held in an inclined position with relation to the bracket 13 to enable the collar to serve as a detent for the load carrying bar 18.

A fulcrum rod 23 extends transversely between the arms 4 and is removably held in the openings 6 by means of nuts 24.

The fulcrum rod 23 passes through an opening near one end of an operating lever 25 to which is pivotally connected, as at 26, 15 a pair of links 27.

A collar 28 is arranged between the head 14 and arm 11 to have passed therethrough the load carrying bar 18, said collar being split to form spaced arms 29 with which is 20 pivotally connected one end of an arcuate shaped link 30 received between said arms and having its other end pivotally connected, as at 31, between the links 27 connected with the operating lever 25.

25 One side edge of the link 30 provides the link with a cam-face 32 having formed thereon for the greater portion of its length teeth 33 which are adapted to be brought into contact with the load carrying bar 18 30 when the operating lever 25 is turned about its pivotal connection with the arms 4 to tightly wedge the load carrying bar between the link and collar, so that the link and collar may co-act in forming a clutch by means 35 of which the load carrying bar may be raised.

By pivotally connecting the link 30 with the collar 28 and providing the link with the cam-face 32, it will be seen that when a load 40 is placed on the load carrying bar 18 any tendency of the load carrying bar to move downwardly through the collar 28 will cause the teeth 33 on the cam-face 32 to more tightly bind against the load carrying 45 bar 18.

When it is desired to use the jack, the operating lever 25 is raised until the collar 28 is brought into contact with the arm 11 which enables the links 27 to move the link 50 30 to a position in which the teeth 33 on the link 30 will be out of engagement with the load carrying bar 18.

With the lever still raised, the collar 20 is manually raised to a horizontal position at 55 which time the load carrying bar will be free to slide through the openings in the heads 11 and 14 and also the collar 28 until one end of the load carrying bar strikes the bottom of the opening 5 at which time the load carrying bar will be in its normal and lowered position.

The jack may now be positioned beside

the weight to be lifted and the weight positioned on the head of the load carrying bar 18.

65

The operator of the jack now starts to lower the operating lever 25, such movement causing the links 27 to turn the link 30 about its pivotal connection with the arms 29 on the collar 28 and tightly wedge the load carrying bar between the teeth 30 and the collar 28.

70

As the operating lever 25 turns about its pivotal connection with the arms 4, the load carrying bar 18 is moved vertically upward 75 by the collar and link 30, such movement causing the arm 21 to assume the position in which the load carrying bar 18 is freely movable through the collar 20.

When the free end of the operator lever 80 25 reaches its limit of downward movement, the weight of the collar 20 causes the collar and arm 21 to assume an inclined position with relation to the bracket 13, so that when the operating lever is again turned about its 85 pivotal connection to cause the collar 28 to contact with the arm 11, downward movement of the load carrying bar will be prevented.

80

The above described movement of the operating handle is continued until the load on the load carrying bar has been moved a sufficient distance from the ground.

From the foregoing description, taken in connection with the accompanying drawing, 90 it is at once apparent that a jack has been provided in which the load carrying bar operating mechanism has been provided with a collar and a link so connected with each other and with the mechanism for operating 95 the load carrying bar that they provide a clutch which will firmly and quickly grip the load carrying bar to enable the same to be raised step by step when said mechanism is operated.

100

Having thus described the invention, what is claimed as new, is:

In a device of the class described, a base having an opening therein, a bracket on said base, a standard on the base having connection with said bracket and braced thereby, a plate on said standard having an arm connected with the base and provided with an opening registering with the opening in the base, a second arm on said plate 110 overlying the first mentioned arm and having an opening therein registering with the opening in the first mentioned arm and base, a lifting bar passing through the openings in said arms and to extend within the opening in the base, and means for operating said lifting bar.

105

In testimony whereof I affix my signature.
PAUL WAGNER.
